United States Patent Office.

SELDEN A. BAILEY, OF WOONSOCKET, RHODE ISLAND, ASSIGNOR TO BAILEY WASHING AND WRINGING-MACHINE COMPANY, OF SAME PLACE.

Letters Patent No. 77,346, dated April 28, 1868.

IMPROVED WRINGING-MACHINE.

The Schedule referred to in these Letters Patent and making part of the same.

TO ALL WHOM IT MAY CONCERN:

Be it known that I, SELDEN A. BAILEY, of Woonsocket, in the county of Providence, and in the State of Rhode Island, have invented certain new and useful Improvements in Wringing-Machines; and do hereby declare that the following is a full, clear, and exact description thereof, reference being had to the accompanying drawings, forming part of this specification, and in which—

Figure 1 represents an end view of a wringing-machine with my improvements attached.

Figure 2, a side view of the same.

Figure 3, a longitudinal section of a portion of one of the rolls, and

Figure 4 a transverse section of the same.

The nature of my invention consists in—

First, forming the teeth of the driving-gears with enlarged extremities, the sections of which are nearly circular in form, with shanks diminishing toward their hub, as shown, for the purpose of enabling them to adapt themselves to the variations of distance between the centre of the rolls caused by the different articles that pass through them, and providing them with flanges, which serve to prevent them from engaging too deeply, and also to prevent end motion and wear of the rolls.

Secondly, in providing an easy adjustment for the rods which stiffen and support the rubber covering of the rolls, so as to give the same sufficient firmness and elasticity, without liability of injury to the rods.

In the accompanying drawings, A A' represent the rolls of the wringing-machine. The rolls are geared at each end by the gears a a', b b', and are driven by the crank, B, upon the shaft of the roll A'. The roll A is susceptible of vertical motion to admit articles of different thicknesses, and is pressed up against roll A' by the springs C. The enlarged and nearly circular extremities of the teeth, with shanks diminishing toward the hub, enable them to work when the rolls are forced apart, and the bluntness of their points prevents the latter from wearing or breaking when so working. The teeth are provided with flanges a² b², a³ b³, which, by coming in contact with the hubs of the opposing gears, prevent the teeth from engaging each other too deeply, and the wear thereby occasioned, and also prevent longitudinal motion and wear of the rolls.

The rolls are constructed in the following manner: Thin sheets of calendered rubber are wound upon a central shaft turned down at its ends to form suitable journals. Stiffening-rods, d, figs. 3 and 4, are arranged around this shaft: The spaces between the rods are then filled with similar rubber, and suitable caps secured at the ends of the rods. By exposure to steam of high temperature, the rubber is welded or united into a solid mass, and the rods and central shaft may be withdrawn from the mould. Before being returned, they receive a coat of copal-varnish, and are wound round with twine, which increases their diameters, and causes them to be a tight fit in the rubber, preventing any movement, and consequent friction. The stiffening-rods are held in position by the collars D, which may be made either in one or two pieces. When in two pieces, as shown, the inner ones have holes drilled through them, in which the rods fit easily, with some little end-play allowed, so as to allow them to spring slightly without bending or breaking. The outer portions of the collars serve as caps to cover the holes and prevent the rods from working through. The collars can be secured upon the shafts by steady-pins, keys, or in any suitable manner.

The machine is put in motion by the crank on the shaft of roll A', which, by the gears on its ends, gives motion to the roll A. The articles to be wrung are passed between the rolls, and when of sufficient thickness to force the latter apart, the elongated elliptical form of the teeth enables the latter to continue in working gear with each other, while the bluntness of their points prevents them from being worn or broken, as they would be if sharp. The teeth-flanges a² b², a³ b³ will strike upon the hubs of the gears opposite to them, should the upper roll be returned too far by the springs C C, and thus prevent the teeth from engaging each other too deeply, while the arrangement of the flanges, as will be seen from fig. 2, obviates end motion of the rolls, and consequent wear. The collars D hold the rods d securely in the rolls, with such an adjustment as to allow

them to spring slightly, when required, forming a roll at once firm and elastic. When the collars are made in one instead of two pieces, the holes are drilled only part way through the solid metal at the bottom of each, serving instead of the separate cap first described.

What I claim, and desire to secure by Letter's Patent, is—

1. Flanged teeth, with their extremities enlarged, and nearly circular in form, and with shanks diminishing toward the hub, substantially as shown and described.
2. A gear having a separate flange on each tooth, as and for the purpose set forth.
3. The collars D, constructed to admit and retain the stiffening-rods of the rolls, substantially as described.
4. The stiffening-rods d, so fitted and held in the collars as to allow end-play, substantially as and for the purpose set forth.

S. A. BAILEY.
